CONTAINER FOR FOOD PRODUCTS

Charles F. Allen and Selwyn Smith, Fort Worth, Tex., assignors, by mesne assignments, of one-third to said Allen, one-third to said Smith, and one-third to J. Pratt Irby, Dallas, Tex.

Application February 14, 1931. Serial No. 515,804

6 Claims. (Cl. 229—4.5)

This invention relates to containers for frozen confections, ice cream, ices, candies, and other food products, and refers more particularly to a container formed by winding overlapping layers 5 of paper or other fibrous material in spiral extension to form a cylindrical shape, the layers being secured together by means of a vegetable glue or paste or any suitable adhesive substance.

The object of this invention is the provision of 10 a container from which the contents may be dispensed by tearing the spiral wound container against the direction of the winding, the under layer or strip, of fibrous material, when pulled, cutting or pulling off the top, or outer layer of 15 material to expose the contents to the extent desired.

The advantage of this invention is that the container is removed from the produce in fractional parts as may be desired, thus facilitating 20 the eating of the contents without touching the same with the hands.

The container, while shown in the drawing in cylindrical shape, may be cone-shaped, or the frustum of a cone, or rectangular in shape, the 25 ends being sealed in the manner specified hereinafter.

In the drawing annexed hereto, with which the following description is made,

Figure 1 is a longitudinal sectional view of a 30 cylindrical container.

Figure 2 is a side elevation.

Figure 3 is a side elevation, showing portions 35 of the plies unwound, to disclose the construction.

Figure 4 is a plan view of the upper disc closure member.

Figure 5 is a cross-section of the disc member.

Described generally, the present invention resides in the novel construction of a container or 40 wrapper, such as may be employed for the packaging of frozen confections or other materials, which is of such character that it may be removed fractionally, to accomplish the progressive shortening of the container to facilitate the dispensing 45 or removal of portions of its contents, while the remainder of the container continues to serve as a holder for the material. The container includes a tubular body member formed of a plurality of plies of thin flexible material, such as paper, one 50 of the plies being formed of a comparatively narrow strip which is wound helically in a tubular shape with the juxtaposed margins of adjacent turns readily separable from each other in the unwinding of the strip, and another ply being formed of a strip which is adhesively secured to

one of the surfaces of the first mentioned strip in such fashion as to hold the turns of the latter in proper relationship and to overlap or bridge the jointure lines of its turns, to form a continuous imperforate tube. The first mentioned strip 60 is stronger or tougher than the sealing strip, so that it will serve, in the process of unwinding it, as a tearing or cutting element effective to separate the other strip progressively along the helical jointure line of the turns of the first mentioned strip. Thus the tube may be progressively shortened to expose and accommodate piecemeal removal of the contents. The tube is provided with appropriate end closures to form a complete 65 container.

Continuing the description, in Figures 1 and 2, the inner layer 2 of fibrous material, in this case a dry, waxed paper is shown, the edge thereof being indicated 2a, in a helical winding. In practice, we have found it of advantage to make this 70 inner layer of heavier or stronger material than the outer layer. The outer or upper layer 1 is wound with edges 1a—1a thereof overlapping the edges 2a—2a of the strip 2, and is adhesively secured to the entire outer surface of the inner 75 layer, to form a continuous imperforate tube.

It will be observed that this manner of forming a container of the above character not only effects the uniting of the spirally wound strips to produce a composite and reinforced supporting wall structure but bridges the principal line of jointure in such a manner that when force is applied to the under strip in unwinding direction it serves to cut or sever the bridging strip along said line of jointure to present a substantially smooth severed surface. Such unwinding may be effected fractionally or continuously throughout the length of the container to dispense the contents as desired. And in this connection it will also be noted that the number 80 of strips may be varied according to the particular operating requirements without departing from the scope or spirit of the invention.

The bottom of the cylinder so formed is sealed by a disc 4 of the same material, of larger diameter than the tube and which is forced up into the tube far enough to allow the extension of the tube below it to form a grip or handle for the person utilizing the container until the contents thereof are entirely consumed. It is understood that this closure member 4 is not limited to a disc as shown in the drawing, but may be an inverted cup, a cap fitting over the outside of said tube, or other closure means as may be desired.

In Figure 3, the container is shown with the spiral strips partially unwrapped to show their relationship.

At the top edge of the container a terminal portion of the strip 2 is accessible for grasping, as by provision of a slit 5 to allow a starting point for the unwrapping process. While we prefer to use a simple slit, or cut, through the wall of the container, as the means of affording such starting point for the unwrapping process, we do not desire to limit ourselves to this particular feature.

The top of the cylinder is sealed with a disc 3 (see Figures 4 and 5) forced down upon the contents. While we prefer to use a flat disc for the top closure member, we do not desire to limit ourselves to this particular means of effecting said closure.

While we prefer to use waxed paper as the material out of which said container is made, we do not wish to limit ourselves to this particular material.

What we claim is:

1. A container for accommodating piecemeal exposure of its contents, comprising an inner strip of sheet material wound helically with margins of juxtaposed turns readily separable from each other in the unwinding of the strip, and an outer strip of sheet material wound helically upon the inner strip with its turns in overlapping relationship to the margins of those of the inner strip, the overlapping portions of said strips being adhesively connected to form a tube, both strips being of thin and readily flexible material, the inner strip being stronger than the outer strip and the latter being of a character facilitating its being torn progressively along the margin of the inner strip by the unwinding of the latter.

46 2. A container as specified in claim 1 and wherein both strips are of paper and the inner strip is of water-repellent character.

45 3. A container comprising a tubular body portion formed of an inner strip of sheet material wound helically in tubular form with the margins of juxtaposed turns readily separable from one another to permit its being unwound progressively, and an outer strip of sheet material wound helically upon and approximately paral-

50 el with the inner strip and adhesively secured upon the outer surface thereof in overlapping relationship to the margins thereof to form a continuous tube, both strips being of readily flexible material and the outer strip being more readily torn than the inner strip, whereby to accommodate progressive tearing of the outer strip along the margin of the inner strip by the unwinding of the latter.

55 4. A container as specified in claim 1 and wherein a terminal portion of the inner strip is accessible for engagement from outside the container to effect its unwinding.

60 5. A container having a body portion formed of a helically wound inner strip of readily flexible sheet material and a helically wound outer strip of readily flexible sheet material adhesively secured upon the inner strip in overlapping relationship to the margins thereof, said connected strips forming a tube, one of said strips being stronger than the other and having the margins of its juxtaposed turns readily separable from one another to permit its being unwound progressively, the other strip being of a character facilitating its being torn progressively along the margin of the stronger strip by the unwinding of the latter, whereby the tube may be progressively reduced in length.

65 6. A container having a two-ply body portion, one of the plies being formed of a strip of flexible sheet material helically wound with the margins of juxtaposed turns close to and readily separable from one another to permit its being unwound progressively and the other ply being formed of a strip of flexible sheet material applied to the surface of the first mentioned strip and overlapping the margins thereof and adhesively secured to the surface of said first mentioned strip to hold the turns thereof in alignment and form a continuous tube, the first mentioned strip being stronger than the second mentioned strip and the latter being of a character facilitating its being torn progressively along the margin of the stronger strip by the unwinding of the same, whereby the tube may be progressively reduced in length.
